TILE FOR SOIL STERILIZATION

Filed July 17, 1930

UNITED STATES PATENT OFFICE

WILLIAM SALISBURY, OF TOLEDO, OHIO

TITLE FOR SOIL STERILIZATION

Application filed July 17, 1930. Serial No. 468,612.

This invention relates to tile for soil sterilization.

This invention has utility when incorporated in systems for transmitting fluids for distribution through soil and in the elements forming the system.

Referring to the drawing:—

Fig. 1 is a perspective view of an installation, parts being broken away;

10 Fig. 2 is a side elevation of a group of the elements of the invention herein, forming a sub-surface transmission line;

Fig. 3 is a view on the line III—III, Fig. 2;

15 Fig. 4 is a perspective view of a modified type of transmission element; and

Fig. 5 is an end elevation of a connecting element between a header and a distribution line.

Steam line or riser 1 is connected to header 2 disposed in soil 3 to have nipples 4 extend therefrom. Conical shaped plastic elements or tile 5 have their reduced ends circular and provided with openings 6 therethrough for slip fit connection with the nipples 4.

20 25 The remote or large end thereof has cross sectional form comprising straight sides 7, 8, 9, forming a polygonal or semi-hexagonal portion. Circular side 10 thereof terminates in flat side extensions 11 which have connecting sides 12 therefrom to the polygonal portion.

This combination circular-polygonal shaped end is provided with chamfer 13 for receiving beveled end 14 of tile element 15 having the cross sectional form of the large end of the conical element 5. This peculiarly shaped tile has many advantages for sub-surface fluid transmission.

The elements 15 are laid in parallel rows 40 extending from the header 2 any desired length, the last tile of each line being capped by saucer-shaped cover 16 of the same material as the tile.

The tile are preferably laid so that the 45 side 8 forms a base therefor, the extensions 11 then form overhangs along the sides thereof. Openings 17 extend radially through the sides 7, 9, just under the overhangs adjacent the connecting faces 12.

50 Steam under pressure may be turned into

the lines formed by these elements and such will be delivered in jets downwardly from the tile into the soil. All of the steam will be so delivered, the interfitting ends and closed line termini preventing other escape. This sub-surface delivery in downwardly directed jets insures a proper depth sterilization while preventing blow-outs or puddles. It has been found that steam under 50 pound pressure in the header will sterilize an area approximately 140 by 50 feet in about 8 hours, killing all the undesirable bacteria without unnecessary flooding.

The overhangs prevent soil working into the openings 17 and also provide pockets 18 therebeneath which aid in initial distribution of the steam from the openings.

The semi-polygonal portion in its interfitting relation prevents rotation of the elements relative to each other maintaining proper alignment of the openings 17.

In some instances circular tile 19 may be used and in order to maintain the openings properly aligned groove 20 is placed along the side thereof to facilitate laying, the workman placing the tile so that the groove is upward and continuous. To insure that alignment is maintained keys 21 may be dropped into the grooves over the joints.

The opening 22 through the tile is preferably circular and while the elements are designed primarily for sterilization, the transmission lines formed thereby may be used for irrigation or fertilizing.

What is claimed and it is desired to secure by United States Letters Patent is:—

1. A tile element having a cross sectional form comprising three flat sides forming a semi-hexagonal portion, a circular side terminating in parallel flat faced extensions, and flat sides connecting the semi-hexagonal portion termini and the extensions, said semi-hexagonal portions having downwardly directed openings therethrough adjacent the connecting sides.

2. A tile element whose cross sectional form comprises a polygonal portion and a circular portion, the circular portion terminating in parallel tangential extensions forming overhangs for the polygonal portion,

said polygonal portion being provided with downwardly directed openings therethrough adjacent the overhangs.

3. A tile element whose cross sectional form comprises a semi-hexagonal portion and a circular portion, the circular portion terminating in parallel tangential extensions forming overhangs for the semi-hexagonal portion, said tile having a series of downwardly extending openings through the semi-hexagonal portion adjacent the overhang which openings each have their termini entirely in opposite sides of a horizontal plane.

4. A tile having a cross sectional form comprising a lower polygonal portion and an upper circular portion forming an overhang for the polygonal portion and a downwardly extending opening through the polygonal portion adjacent the overhang.

5. A tile having a cross sectional form comprising a lower polygonal portion and an upper circular portion forming an overhang for the polygonal portion and a downwardly extending opening through the polygonal portion adjacent the overhang.

6. A tile having a cross sectional form comprising a lower polygonal portion and an upper circular portion forming an overhang for the polygonal portion and a downwardly extending opening through the polygonal portion adjacent the overhang, the inner termini of said opening being above said overhang.

In witness whereof I affix my signature.

WILLIAM SALISBURY.
